US00D778330S

(12) **United States Design Patent** (10) **Patent No.:** **US D778,330 S**
(45) **Date of Patent:** **** Feb. 7, 2017**

(54) **DOUBLE-SIDED TANGENTIAL CUTTING INSERT**

(71) Applicant: **Kennametal Inc.**, Latrobe, PA (US)

(72) Inventors: **Xiangdong Daniel Fang**, Brentwood, TN (US); **Jean-Luc Dufour**, Franklin, TN (US); **Lance Brunetto**, Greensburg, PA (US); **Kent Mizgalski**, Stahlstown, PA (US); **David Wills**, Greensburg, PA (US); **David Cope**, Mayfield Heights, OH (US)

(73) Assignee: **KENNAMETAL INC.**, Latrobe, PA (US)

(**) Term: **15 Years**

(21) Appl. No.: **29/541,311**

(22) Filed: **Oct. 2, 2015**

Related U.S. Application Data

(63) Continuation-in-part of application No. 14/801,181, filed on Jul. 16, 2015.

(57) **CLAIM**

The ornamental design for a double-sided tangential cutting insert, as shown and described.

DESCRIPTION

FIG. 1 is an isometric view of the double-sided tangential cutting insert;

FIG. 2 is a front elevational view of the double-sided tangential cutting insert of FIG. 1;

FIG. 3 is a rear elevational view of the double-sided tangential cutting insert of FIG. 1;

FIG. 4 is a right side elevational view of the double-sided tangential cutting insert of FIG. 1;

FIG. 5 is a left side elevational view of the double-sided tangential cutting insert of FIG. 1;

FIG. 6 is a top plan view of the double-sided tangential cutting insert of FIG. 1; and,

FIG. 7 is a bottom plan view of the double-sided tangential cutting insert of FIG. 1.
